[57] **CLAIM**

The ornamental design for a holder for pens, pencils and the like, as shown and described.

DESCRIPTION

FIG. 1 is a perspective view of a holder for pens, pencils and the like showing our new design, the utensils depicted by means of broken lines being for illustrative purposes only and forming no part of the claimed design;

FIG. 2 is a top plan view thereof;

FIG. 3 is a front elevational view thereof;

FIG. 4 is an elevational view of one side thereof;

FIG. 5 is an elevational view of the other side thereof;

FIG. 6 is a rear elevational view thereof; and,

FIG. 7 is a bottom plan view thereof.
